(57) **CLAIM**

The ornamental design for a tattoo cartridge, as shown and described.

DESCRIPTION

FIG. 1 is a top perspective view of a first embodiment of a tattoo cartridge showing my new design.

FIG. 2 is a bottom perspective view thereof.

FIG. 3 is a front elevational view thereof.

FIG. 4 is a rear elevational view thereof.

FIG. 5 is right-side elevational view thereof.

FIG. 6 is a left-side elevational view thereof.

FIG. 7 is a top plan view thereof.

FIG. 8 is a bottom plan view thereof.

FIG. 9 is a top perspective view of a second embodiment of the tattoo cartridge, showing my new design.

FIG. 10 is a bottom perspective view thereof.

FIG. 11 is a front elevational view thereof.

FIG. 12 is a rear elevational view thereof.

FIG. 13 is right-side elevational view thereof.

FIG. 14 is a left-side elevational view thereof.

FIG. 15 is a top plan view thereof; and,

FIG. 16 is a bottom plan view thereof.

The broken lines showing the grip and machine are for the purpose of illustrating unclaimed subject matter that form no part of the claimed design.
